(57) **CLAIM**

The ornamental design for a lidar apparatus, as shown and described.

DESCRIPTION

FIG. 1 is a front perspective view of a lidar apparatus showing our design.

FIG. 2 is a rear perspective view of the lidar apparatus in FIG. 1.

FIG. 3 is a front elevation view of the lidar apparatus in FIG. 1.

FIG. 4 is a rear elevation view of the lidar apparatus in FIG. 1.

FIG. 5 is a left side elevation view of the lidar apparatus in FIG. 1.

FIG. 6 is a right side elevation view of the lidar apparatus in FIG. 1.

FIG. 7 is a top plan view of the lidar apparatus in FIG. 1; and,

FIG. 8 is a bottom plan view of the lidar apparatus in FIG. 1.

The broken lines in the drawings illustrate portions of the lidar apparatus that form no part of the claimed design.
